(57) **CLAIM**

The ornamental design for a sink configuration having a backsplash, rim and towel bar, as shown and described.

DESCRIPTION

FIG. 1 is a perspective view taken from the top, front and right side of a sink configuration having backsplash, rim and towel bar showing our new design;

FIG. 2 is a top plan view thereof;

FIG. 3 is a front view thereof;

FIG. 4 is a bottom view thereof, and of the sink configuration having backsplash, rim, and towel bar shown in FIGS. 16 and 25;

FIG. 5 is a right side view thereof;

FIG. 6 is a perspective view taken from the top, front and right side of a second embodiment of FIG. 1, the only differences being the number and shape of the bowls;

FIG. 7 is a top plan view of the sink configuration having a backsplash, rim and towel bar shown in FIG. 6;

FIG. 8 is a front view of the sink configuration having a backsplash, rim and towel bar shown in FIG. 6;

FIG. 9 is a bottom view of the sink configuration having a backsplash, rim and towel bar shown in FIGS. 6, 19 and 29; FIG. 10 is a right side view of the sink configuration having a backsplash, rim and towel bar shown in FIG. 6;

FIG. 11 is a perspective view taken from the top, front and right side of a third embodiment of FIG. 1, the only differences being the number and shape of the bowls;

FIG. 12 is a top plan view of the sink configuration having a backsplash, rim and towel bar shown in FIG. 11;

FIG. 13 is a front view of the sink configuration having a backsplash, rim and towel bar shown in FIG. 11;

FIG. 14 is a bottom view of the sink configuration having a backsplash, rim and towel bar shown in FIGS. 11, 22 and 33;

FIG. 15 is a right side view of the sink configuration having a backsplash, rim and towel bar shown in FIG. 11;
FIG. 16 is a top plan view of a fourth embodiment of FIG. 1, the only difference being the top edge of the backsplash;
FIG. 17 is a front view of the sink configuration having a backsplash, rim and towel bar shown in FIG. 16;
FIG. 18 is a right side view of the sink configuration having a backsplash, rim and towel bar shown in FIG. 16;
FIG. 19 is a top plan view of a fifth embodiment of FIG. 1, the only differences being the number and shape of the bowls and the top edge of the backsplash;
FIG. 20 is a front view of the sink configuration having a backsplash, rim and towel bar shown in FIG. 19;
FIG. 21 is a right side view of the sink configuration having a backsplash, rim and towel bar shown in FIG. 19;
FIG. 22 is a top plan view of a sixth embodiment of FIG. 1, the only differences being the number and shape of the bowls and the top edge of the backsplash;
FIG. 23 is a front view of the sink configuration having a backsplash, rim and towel bar shown in FIG. 22;
FIG. 24 is a right side view of the sink configuration having a backsplash, rim and towel bar shown in FIG. 22;
FIG. 25 is a perspective view taken from the top, front and right side of a seventh embodiment of FIG. 1, the only difference being the top edge of the backsplash;
FIG. 26 is a top plan view of the sink configuration having a backsplash, rim and towel bar shown in FIG. 25;
FIG. 27 is a front view of the sink configuration having a backsplash, rim and towel bar shown in FIG. 25;

FIG. 28 is a right side view of the sink configuration having a backsplash, rim and towel bar shown in FIG. 25;
FIG. 29 is a perspective view taken from the top, front and right side of an eighth embodiment of FIG. 1, the only differences being the number and shape of the bowls and the top edge of the backsplash;
FIG. 30 is a top plan view of the sink configuration having a backsplash, rim and towel bar shown in FIG. 29;
FIG. 31 is a front view of the sink configuration having a backsplash, rim and towel bar shown in FIG. 29;
FIG. 32 is a right side view of the sink configuration having a backsplash, rim and towel bar shown in FIG. 29;
FIG. 33 is a perspective view taken from the top, front and right side of a ninth embodiment of FIG. 1, the only differences being the number and shape of the bowls and the top edge of the backsplash;
FIG. 34 is a top plan view of the sink configuration having a backsplash, rim and towel bar shown in FIG. 33;
FIG. 35 is a front view of the sink configuration having a backsplash, rim and towel bar shown in FIG. 33; and,
FIG. 36 is a right side view of the sink configuration having a backsplash, rim and towel bar shown in FIG. 33.
The drawings do not include a view from the back, as the back is unornamented.
